UNITED STATES PATENT OFFICE.

CHRISTOPHER STRAUB, OF EAST ELMHURST, NEW YORK, ASSIGNOR, BY MESNE ASSIGNMENTS, TO ASTORIA IMPORTING AND MANUFACTURING CO. INC.

VENEER-CUTTING MACHINE.

Application filed February 5, 1925. Serial No. 6,917.

This invention relates to rotary veneer cutting machines and more particularly to means for securing the block of wood in operative position in connection therewith. It has heretofore been proposed, particularly in connection with one-half rotary veneer cutting machines, to secure the block of wood to the stay-log by providing a multiplicity of screws passing through appropriate apertures in the stay-log which are screwed into the log from which the veneer is to be cut to hold the same firmly in operative position. This method of securing the log has been open to the objection that that portion of the block into which the screws extend is so mutilated thereby as to be unfitted for use. The present invention has for its object to provide means for securing the block to the stay-log which will injure minimum portions of the block whereby a greater proportion thereof may be availed of in the manufacture of veneer. Accordingly, chucks or dogs are provided adjustably mounted upon the stay-log to engage the ends of the block from which the veneer is to be taken and retain the same rigidly in operative position with respect to the stay-log. More particularly a chuck or dog, movable with respect to the stay-log, is adapted to be secured in fixed position with respect thereto and is formed on the face adjacent the block with a plurality of knife edges adapted to engage the end of the block, a similar chuck facing in the opposite direction to engage the other end of the block. If desired means may be provided in connection with one or both chucks to adjust the position thereof with respect to the stay-log to provide a more rigid engagement of the block therebetween. Certain of the knife edges on the chucks may be beveled to provide a wedging action which will force the block downwardly against the stay-log and thus contribute to the rigid retention thereof in position.

It sometimes happens that the flitches or blocks of wood have defects in their ends which makes it difficult to grip the ends firmly by the chucks as just described. In this situation supplemental chucks may be provided which are mounted upon the usual chucks to provide knife edges to grip an additional area of the ends of the blocks. More particularly the supplemental chuck is adapted to engage with the top of the main

chuck and to be detachably secured thereto and is provided with additional knife edges to be disposed above and co-operating with the knife edges of the main chuck.

For a more detailed description of the invention reference will now be had to the accompanying drawing illustrating a preferred embodiment thereof and in which:

Figure 1 is a view looking from above and showing a block of wood in position upon the stay-log of a one-half rotary veneer cutting machine and retained in position by means of chucks or dogs according to the present invention.

Figure 2 is a view in side elevation and partly in section in the plane indicated by the line 2—2 in Figure 1 and looking in the direction of the arrows and showing the manner of adjustment of the dogs and the engaging means for the wood.

Figure 3 is an enlarged view taken on the plane indicated by the line 3—3 in Figure 2 and looking in the direction of the arrows and showing a dog mounted upon the stay-log and the knife edges which engage the block of wood shown in broken lines.

Figure 4 is a view in isometric projection of the supplemental chuck showing the location of the knife edges.

Figure 5 is an isometric view showing the supplemental chuck in operative position in relation with a main chuck.

Figure 6 is a view in rear elevation showing the supplemental dog or chuck mounted upon the main dog, the preferred means of securing the two together being illustrated as a spring pressed latch.

In the manufacture of veneer in a one-half round rotary veneer cutting machine a block of wood *a* generally semi-circular in cross section from which the veneer is to be cut is mounted upon a stay-log *b* which is adapted to be rotated through 180° to carry the block *a* against a knife edge which removes a layer of veneer. The stay-log is flat along its upper section as at *b'* to receive the flat surface of the wooden block *a* and forms the mid-section of a substantially round axle *B* carried between a pair of gear wheels *c* which mesh with suitable machinery to rotate the stay-log through 180° about its longitudinal axis. Heretofore it has been the practice to form in the stay-log a plurality of series of holes through which screws may pass to engage the block of wood. The use

of such screws, however, mutilates the block of the rod f^2 to bear against the face e^6 to such degree as to render unfit for use a considerable portion thereof. To avoid this waste applicant proposes to provide dogs or 5 chucks d and e formed with a plurality of knife edges to engage the ends of the block and retain it in operative position with respect to the stay-log b . The stay-log is normally flat and of greater width in a transverse direction than the round portion of the axle B thus forming what amounts to flanges b^2 upon opposite sides thereof which may be conveniently engaged by downwardly extending portions d' or e' as the case may be, 10 formed inwardly with recesses, say d^2 , to receive the flanges b^2 . Preferably the flanges b^2 and the recesses, say d^2 , so cooperate as to permit the dogs to be slid back and forth along the length of the stay-log. The chuck 15 is preferably semi-circular in cross section as shown clearly in Figure 3 in order to provide a surface to co-operate with as great an area of the end of the block as possible without interfering with the knife edges during 20 the movement of the block. Upon one face of the chuck and at the upper periphery thereof there is formed a semi-circular knife edge d^3 or e^3 while radially disposed knife edges d^4 and e^4 , which in the illustrated embodiment are three in number, are formed 25 below the semi-circular knife edges d^3 , e^3 , respectively.

In securing the block of wood to the stay-log one of the dogs is adapted to be disposed 30 in predetermined position with respect to the stay-log and secured in such position. The dog is preferably secured in predetermined position by adjustable devices which, in the illustrated embodiment, take the form of 35 teeth b^3 formed centrally of the stay-log which are adapted to be engaged by a finger d^5 pivotally mounted upon the face of the dog d . The series of teeth are of limited extent longitudinally of the stay-log but are 40 sufficient in number to allow a degree of adjustment of the dog d to permit accommodation 45 of blocks of wood of different length. Upon the opposite end of the stay-log is mounted a dog e slidable upon the flanges b^2 50 and provided with inwardly facing teeth e^3 , e^4 similar in every respect to the teeth d^3 , d^4 . No ratchet is provided on the chuck e , however, but outwardly of the dog e there is disposed what may be termed a nut f slid- 55 able in a similar manner with respect to the stay-log and having pivoted on its outer face a finger f' adapted to engage inwardly facing teeth b^4 formed on the upper face of the stay-log at that end. Means to adjust 60 the position of the chuck e with respect to the nut f are shown as a threaded rod f^2 rotatable within a threaded aperture f^3 in the nut f and bearing against the proximate face e^5 of chuck e . Rotation of the handle 65 f^4 in appropriate direction will cause the end

of the chuck to force the chuck away from the face and cause the knife edges e^3 and e^4 to bite into the end of the wooden block a . The method of securing the block of wood to the stay-log will be apparent from the foregoing description. The chuck d is first positioned at an appropriate place dependent upon the length of the block of wood a and maintained in such predetermined position by the engagement of the finger d^5 with a tooth b^3 . The block of wood a is placed upon the stay-log and forced against the knife edges to engage the same. The nut f and chuck e are then moved along the stay-log to approximately appropriate position to permit the knife edges e^3 , e^4 to engage the block of wood and one of the teeth b^4 is engaged by the finger f' . The threaded rod f^2 is then rotated in appropriate direction to bear against the face e^5 of chuck e and the pressure set up thereby causes the knife edges e^3 , e^4 to bite into the block of wood. 75 80 85

Preferably knife edges d^2 and e^2 are beveled in a downwardly facing direction as indicated at d^6 , e^6 . It will thus be seen that when the knife edges are caused to bite into the log the beveled edges of the plates will have a tendency to force the block downwardly against the stay-log and hold the same rigidly in position. 90 95

While the dog just described is effective in securing a block of wood to a one-half rotary veneer cutting machine, it may also be found desirable to secure extra flitches or blocks of wood to the stay-log or the block may have such defects in its ends as to make it difficult to securely grip the same with the dogs. It is, therefore, proposed to provide a supplemental chuck or dog which may be superimposed upon the main dog and provided with knife edges extending in the same general direction as the knife edges on the main dog whereby a greater area of the ends of the block may be engaged by knife edges. Accordingly a supplemental dog g may be provided having at its one end an arcuate knife edge g' beveled at its lower side as at g^2 to provide wedging action as hereinbefore described in connection with the knife edges e^5 and if desired a vertically disposed knife edge g^3 . The supplemental dog g is adapted to be secured above the main dog, say e , (or d) so that the knife edges g^2 , g^3 lie in the same vertical plane with the knife edges of the main dogs. To provide for ready attachment and removal it is preferred to form a slot shown in the drawings as e^7 in the dog e . The side walls of the slot e^7 preferably taper downwardly and outwardly so that the slot is of greater width at its bottom. A co-operating portion g^4 of the supplemental dog is adapted to be slid within the slot e^7 as clearly illustrated in the drawings. To prevent displacement of the sup- 100 105 110 115 120 125 130

plemental dog a latch of any convenient construction may be provided. In Figure 6 there is illustrated a pin *h* formed with a shoulder *h'* passing through a hole *g*⁵ in the supplemental dog and entering a hole *e*⁸ in the main dog *e*. The shoulders *b* serve not only as engaging surfaces for the fingers or a tool whereby the pin *h* may be moved upwardly out of the recess *e*⁸ but also as a bearing for the resilient element or coil spring *i* tending to force the pin downwardly for engagement with the hole in the main dog.

It will be evident that means have been provided which are readily adjustable to engage a block of wood from which veneer is to be peeled and retain the same in operative position with respect to the stay-log whereby the knife edges may operate upon the wood with precision and without danger of the block slipping and spoiling the cut.

Various modifications may be made in the method of adjustment of the chucks with respect to each other and the stay-log as well as in the number and configuration of the wood engaging instrumentalities formed thereon and no limitation is intended by the foregoing description except as indicated in the appended claims.

30. What I claim is:

1. In a half round rotary veneer cutting machine, the combination with a stay-log operatively rotatable about its own axis, of means slidable on the stay-log to secure a half round flitch thereto and means cooperating with the stay-log to adjustably position the first named means.

2. In a rotary veneer cutting machine, the combination with an axially rotatable support for a block of wood, of a plurality of chucks carried with the support and having knife edges on opposed faces to engage the respective ends of the block of wood, and means to adjustably secure one of the chucks in predetermined position to the support, a base, means to adjustably secure the base in predetermined position with respect to the support, and means on the base to adjust another of the chucks with respect to the base and the support and the first named chuck.

3. In a rotary veneer cutting machine, the combination with a support for a block of wood, rotatable about its axis of a chuck to engage an end of the block, pawl and ratchet means to position the chuck with respect the support, a stop, pawl and ratchet means to secure the stop in predetermined position with respect to the support, a chuck to engage the other end of the block of wood, and means to adjust the relative relation of the stop and last named chuck.

4. In a rotary veneer cutting machine, the combination with a support for a block of

wood, of a chuck slidable on the support 65 and having an inverted U-shaped knife blade and radially disposed knife blades within the U-shaped portion.

5. In a rotary veneer cutting machine, the combination with a support for a block of 70 wood, of a chuck having an inverted U-shaped knife blade beveled on the lower side of its edge and radially disposed knife blades within the U-shaped portion.

6. In a rotary veneer cutting machine having a stay-log for the support of a flitch, in combination a main chuck adjustably mounted on the stay-log, a supplemental chuck formed with a knife edge upon one face thereof, and means to removably secure the 80 supplemental chuck to the main chuck.

7. In a half round rotary veneer cutting machine, the combination with an axially rotatable stay-log and a main chuck slidable on the stay-log, of a supplemental chuck formed 85 with a curvilinear knife blade upon one face thereof, and means to removably secure the supplemental chuck to the main chuck.

8. In a half round rotary veneer cutting machine, the combination with an axially rotatable stay-log and a main chuck slidable 90 thereon, of a supplemental chuck formed with a curvilinear knife blade and a vertically disposed knife blade upon one face thereof, and means to removably secure the supplemental chuck to the main chuck.

9. In a rotary veneer cutting machine having a stay-log for the support of a flitch the combination with a main chuck for a rotary veneer cutting machine of a supplemental 100 chuck formed with a curvilinear knife blade beveled on the lower side of its edge and a vertically disposed knife blade upon one face thereof, and means to removably secure the supplemental chuck to the main chuck.

10. The combination, in a veneer cutting machine having a rotatable stay-log for the support of a flitch, with a main chuck formed with knife blades upon one face thereof and a slot in its upper surface of a supplemental 110 chuck formed with knife blades to co-operate with the knife blades of the main chuck and a lug to engage the slot, and means to removably secure the supplemental chuck to the main chuck.

11. The combination, in a veneer cutting machine having a rotatable stay-log for the support of a flitch, with a main chuck formed with knife blades upon one face thereof and a slot in its upper surface of a supplemental 120 chuck formed with knife blades to co-operate with the knife blades of the main chuck, and a spring pressed pin carried with the supplemental chuck and engaging a recess in the main chuck.

This specification signed this 2d day of February, A. D. 1925.

CHRISTOPHER STRAUB.
